THERMOSTATIC UNIT

Joseph J. McMahon, Lowell, Mass., assignor to
 Clifford Manufacturing Co., Boston, Mass., a
 corporation of Delaware

Application December 19, 1939, Serial No. 310,005

1 Claim. (Cl. 297—8)

The present invention relates to thermostatic units, and is more particularly concerned with sealed units embodying a diaphragm or its equivalent and filled with thermostatic fluid which may be in the nature of a saturated vapor to control by expansion and contraction of the diaphragm a switch, valve or other outside element in accordance with temperature variations at a point which may be more or less remote from the actuating apparatus itself.

Units of this character invariably employ a capillary in connection with the diaphragm unit, the combination of the two elements providing a sealed space, and the capillary affording communication between the diaphragm and the region to be controlled. By virtue of this construction the actual controlled valve or switch may be located where most convenient regardless of the location of the controlled region. This type of apparatus finds employment in the control of cooking ovens, refrigerators and the like. Difficulty has invariably been experienced in the past in providing a union between the capillary and the diaphragm or housing within which the diaphragm is contained of such a character that the capillary would withstand the rough uses to which it is subjected without premature breakage and destruction of the unit.

It is accordingly the purpose and object of the present invention to reorganize and improve constructions of this character in such a manner that the general construction of unit shall be free from the weaknesses which have heretofore been present.

With this and other objects in view, the various features of the invention consist in certain novel features of construction, combinations and arrangements of parts hereinafter described and claimed, the advantages of which will be obvious to those skilled in the art from the following description.

In the accompanying drawing illustrating the preferred form of the invention, Fig. 1 represents a bottom plan view of a diaphragm-containing housing with attached capillary; Fig. 2 is a section in elevation of the housing shown in Fig. 1 with a capillary extending therefrom; Fig. 3 is a section similar to Fig. 2 of a slightly modified form of structure; and Fig. 4 is a detail illustrating a section upon the line 4—4 of Fig. 1, showing the method of supporting and connecting the capillary to the bottom of the housing.

As shown in the illustrated embodiment of the invention, the unit comprises essentially a drawn metal housing 10, generally cup-shaped and hav-

ing a flat bottom portion 12 and a peripheral side wall 14 terminating in an attaching flange 16, having openings 18 for the use of attaching bolts, screws or the like. The housing may preferably be drawn from sheet metal, and is provided adjacent the open end with a peripheral seating shoulder 19, as indicated more particularly in Fig. 2. The diaphragm unit assembled within the housing may take the form of a bellows 20, having one integrally closed end 22, and provided with a radial attaching flange 24 at its open end which engages with the seating shoulder 19. The unit is anchored to the housing at its open end through a head 26 seated at its margin upon the shoulder 18 and soldered thereto to permanently anchor the bellows or diaphragm therein. This head closes the normally open end of the housing, and is provided at its central portion with an opening 28 surrounded by a depressed portion 30 of the head for a purpose to be presently described.

The opposite or movable end of the bellows unit is drawn inwardly at 32, and has connected thereto a head 34 internally threaded at 35 and receiving a threaded pin 38 which extends outwardly beyond the head and is employed as an actuator for the engagement of an outside element such as the movable part of a switch or valve (not shown). In order to prevent the entrance of solder, tinning compound or the like within the space inside of the bellows unit and beneath the cap, it will be noted that the head is provided with a shoulder 36 normally seating upon the surface 30 to limit the outward movement of the pin. The space therewithin may be sealed, if desired, by a compressible gasket 40, as indicated in Fig. 2. The bottom of the cup-shaped unit, as indicated, may be pierced at 42 with an inwardly directed opening having a surrounding sleeve 44. The bottom is also provided with a generally U-shaped protuberance 46, as shown more particularly in Fig. 1, which closely surrounds the opening 42 at the base of the U, the legs of the U extending from the opening 42 across the bottom of the peripheral edge thereof, forming essentially a channel or trough 48, the bottom of which may be flush with the plane of the cup bottom, and which receives and fits a capillary 50 throughout a substantial portion of its length, as again indicated in Figs. 1 and 2, the end of the capillary being turned angularly with relation to this portion and extending through the opening 42 at 52. The capillary is bonded to the cup by a solder material indicated generally at 62, which is directed against the

bottom of the cup, flows into the space between the capillary and the central opening, and also throughout the length of the trough 48 encompassing the capillary. This construction has been found exceedingly desirable, as it permits the capillary to be bonded rigidly to the fixed housing without liability of breakage, and furthermore permits the employment of a soft low temperature solder due to the area of engagement which does not injuriously anneal the material of the capillary in the soldered region.

The capillary may have any appropriate length desired and depending upon the remoteness of the control region, and is filled, together with the space 60 inside of the housing and surrounding the diaphragm, with a suitable thermostatic fluid, the whole interior space having been first exhausted of air as is usual in this type of apparatus. After evacuating and sealing, the open end of the capillary through which the fluid is introduced is crimped at 63 and closed by solder, as indicated at 64.

It will be noted that the construction shown in Fig. 3 represents a slight modification of the structure shown in Figs. 1 and 2. In this structure the housing shown at 10 is slightly less in depth and is provided with a smaller bellows unit 12. The bellows unit is anchored to the housing in the same manner as previously described, and the movable end of the unit is thrown inwardly

30 a sufficient depth to provide an actuator button 74, which extends through the attached head 16, this button taking the place of the pin 38 previously described. The formation of the bottom 5 of the housing and the attachment of the capillary thereto is identical with that described in Figs. 1 and 2, the bottom being provided with a central opening 78 and a generally radial trough 80 within which the capillary 32 is received.

10 What is claimed is:

15 In a thermostatic unit, a generally cup-shaped metal housing having bottom and peripheral walls, a flexible diaphragm unit cooperating with 20 said bottom and peripheral walls to provide a closed space within said housing, an aperture in said bottom wall, the metal of said bottom wall being formed to provide a trough-like depression of arcuate cross-section extending from said 25 aperture to the periphery of said bottom wall, a capillary extending through said aperture and along the bottom of said trough-like depression, said depression having a diameter substantially equal to the external diameter of said capillary, and solder material partially overlying said capillary throughout the length of said depression to retain said capillary within said depression and to seal said aperture around said capillary.

JOSEPH J. McMAHON.
